(57) **CLAIM**

The ornamental design for an outdoor projection screen, as shown and described.

DESCRIPTION

FIG. 1 is a front, left and top perspective view of an outdoor projection screen, showing my design.

FIG. 2 is a rear, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1.

FIG. 11 is an enlarged view of detail 11 in FIG. 2.

FIG. 12 is an enlarged view of detail 12 in FIG. 2.

FIG. 13 is an enlarged view of detail 13 in FIG. 3.

FIG. 14 is an enlarged view of detail 14 in FIG. 5.

FIG. 15 is an enlarged view of detail 15 in FIG. 7.

FIG. 16 is an enlarged view of detail 16 in FIG. 7; and,

FIG. 17 is an enlarged view of detail 17 in FIG. 8.

The broken lines depict portions of the outdoor projection screen that form no part of the claimed design. The dot-dash broken lines in FIGS. 1-3, 5, 7, and 8-17 depict the boundaries of the enlargements that form no part of the claimed design.

1 Claim, 17 Drawing Sheets
